[DESIGN.]

ROBERT WOOD.

Hitching Post.

No. 5,874.

Patented May 21, 1872.

Robert Wood
Inventor

Washington, D. C. - May 21, 1872.

5,874

UNITED STATES PATENT OFFICE.

ROBERT WOOD, OF PHILADELPHIA, PENNSYLVANIA.

DESIGN FOR HITCHING-POST.

Specification forming part of Design No. 5,874, dated May 21, 1872.

Specification describing a Design for a Hitching-Post, invented by ROBERT WOOD, of the city and county of Philadelphia, State of Pennsylvania.

The nature of my design is fully represented in the accompanying photographic illustration, to which reference is made.

What I claim as my invention is—
A design for a "hitching-post" in the form, shape, and costume of a "Coolie" or "Chinee," as shown.

Witnesses: ROBERT WOOD.
THOS. S. ROOT,
SAMUEL FISHER.
